TROUSERS

Tobias Kotzin, Los Angeles, Calif.

Application August 27, 1945, Serial No. 612,797

4 Claims. (Cl. 2-227)

1 This invention relates to garments, and more particularly to trousers, shorts, or combination garments, usually made with double needle, double lap seams, and generally used for work, utility, or sports wear.

In many of these garments the body material forming the front of the garment leg overlaps the material forming the back. A double row of stitching is usually used to fasten the parts together, thus providing a side seam. The side pocket utilizes a third piece of the body material as a facing or "pocket bearer" for the exposed inner side of the pocket. The upper side of the front piece is not caught in the side seam, and is used to form the outer side of the pocket opening.

In such garments, bar tacks are usually sewn at the ends of the pocket openings as a reinforcement, but such bar tacks are not always effective in preventing the tearing of the pockets at such points of strain.

It is one of the objects of this invention to prevent the tearing of the front pockets at such points by actually anchoring the ends of the pocket opening in and under the seam and to restrict the stresses to which said openings are subjected in actual use to multiple layers or plies of fabric, and to distribute the attaching stitching over a broader area, so as practically to eliminate tearing at these usually vulnerable points.

In the usual construction, where the front is lapped over the back to obtain a clean finish, the portion of the garment from the bottom of the side pocket to the top of the band, or waist portion, may be joined together by means of several stitching operations; and the side seam is double lap seamed from the bottom of the garment to the point where the previous joining starts. This is a slow and much more expensive method.

When, in this usual method of lapping the front part over the back, a continuous seam from top to bottom is used, it becomes necessary to feed, through the folder of the seaming machine, the lower portion of the folded front edge of the pocket, and to fold said folded edge around the convex side of the folder attachment, as well as around the edge of the seam.

Because of the number of plies and the folded edges which must be fed around the outside edge of the side seam, much difficulty is encountered in performing the operation, and the best quality of workmanship is practically unattainable. To facilitate this operation, some of the underneath plies are sometimes trimmed out, or the front is notched, greatly weakening the construction.

In any of the usual constructions, using a continuous seam and folding or lapping the front

part over the back, there is an additional inherent weakness at the point where the bottom edge of the pocket opening crosses the side seam. All of the strain put upon the pocket opening is taken by the top stitch of the first row of stitching; and, as one stitch breaks, the strain applies to the next, so that only the top stitch of each row of stitching is carrying the load.

Where bar tacks are used, they may tend to reinforce these first stitches when placed in exactly the proper position. Such an advantageous positioning is often neglected. In addition, there is a space between the two rows of stitching where the pocket edge crosses the seam, and which, unless stitched down by a separate operation, is a potential hazard and weakness, for it presents an unattached edge which may be inadvertently caught.

In the improved construction, the folded edge of the front pocket lies practically flat where it becomes a part of the seam. It feeds into the concave side of the folder of the seaming machine readily, and is covered by the seam, being caught and securely held and gripped between the lapping seam parts of the front and back portions of the garment.

Furthermore, this construction makes it possible to catch, with a bar tack in the seam, the full thickness of the folded edge of the front pocket opening, so that the strain is carried by the full number of plies of body and pocketing material. The effect of this construction is to incorporate this pocket opening into the structure as an integral part of the garment.

This invention possesses many other advantages, and has other objects which may be made more clearly apparent from a consideration of one embodiment of the invention. For this purpose there is shown a form in the drawings accompanying and forming part of the present specification. The form will now be described in detail, illustrating the general principles of the invention; but it is to be understood that this detailed description is not to be taken in a limiting sense, since the scope of this invention is best defined by the appended claims.

Referring to the drawings:

Figure 1 is a fragmentary side elevation of a pair of trousers embodying the invention, a part of the pocket construction being broken away to illustrate a feature of the device;

Fig. 2 is a fragmentary enlarged sectional view, taken along plane 2-2 of Fig. 1, the folds of the cloth pieces being separated slightly for the sake of clarity; and

Fig. 3 is an enlarged section, taken along plane 3-3 of Fig. 1, the folds being separated slightly.

Each of the legs of the trousers is formed of a back piece 1 and a front piece 2. At the top edge of these pieces, there is sewn a waist-forming portion 3.

The edge of back piece 1 overlaps the edge of the front piece 2. The overlap may be accomplished in any usual manner as indicated: for example, in Fig. 3, where the edge 4 of the piece 1 is folded over and then underneath the folded edge 5 of the front piece 2. There are usually two lines or rows of stitching 6 and 7 to form the seam 20 along the side of the garment.

The pocket construction, illustrated most clearly in Figs. 1 and 2, is simplified by the aid of the present invention. The front piece 2 at its upper portion has an edge 8 which, in this instance, is shown as slanting so that the edge 8 is free of the seam 20. Thus, the edge 8 is unattached except at its bottom end which engages the seam 20, and at its top end which is attached to the waist portion 3. Accordingly, this edge 8 forms one side of the pocket opening. The other side of the pocket opening is formed by the folded-over edge 9 of the back piece 1.

The pocket 10, which may be made of stout cotton material, such as duck, drill, or the like, has one of its sides folded and overlapped underneath the folded edge 9 of back piece 1, as shown in Fig. 2. The other side of the pocket opening is attached to the edge 8, as by the line or row of stitching 11.

In order to avoid unsightly exposure of the pocket through the opening between the edges 8 and 9, a lining or facing 12 is provided for that portion of the pocket 10 which is adjacent the edge 9. This lining or facing can be made of the same material as the pieces 1 and 2, and is wide enough to underlie the edge 8. Its outline is indicated in Fig. 1 in dotted lines.

To facilitate attachment of the facing and to simplify the sewing, this facing has a straight side or edge 21 that is sewn to the pocket 10 by a straight line or row of stitching 22. Furthermore, this edge 21 is preferably the selvage edge, so that it is then unnecessary to turn this edge.

The process of sewing the pieces 1 and 2 and the pocket 10 together is considerably simplified. First of all, the pocket bearer facing 12 is sewed in place by the line of stitching 22. The lower edge of the facing can be caught in the "closing" stitching at the bottom of the pocket, and which can be accomplished best while the pocket is separate from the rest of the garment. The completed pocket is then sewn to the front 2. This involves fitting and stitching the edge of the pocket to the edge of the front 2 to form the front edge 8, and then fitting the top of front 2 to the pocket bearer 12. Then the top of the pocket may be stitched, as indicated at 23, to the top of the front 2. In this way, the top of the pocket is held in place for the subsequent banding operation. The bottom of the front edge 8 of the pocket opening is also fitted to the pocket bearer 12 to hold it in proper position for sewing. After the pocket is thus attached to the front 2, the double seam 6, 7 may be run through the folder of the sewing machine.

The inventor claims:

1. In a trouser: pieces forming, respectively, the front and back of the trouser leg, the back piece overlapping the outer face of the front piece; and said front piece having an upper portion defining one edge of a pocket opening, said portion being unattached to the back piece, the

front and back pieces being otherwise sewed together at the side of the leg; and means forming a pocket having an opening, said means at one side of the opening being attached to said upper portion, and at the other side of the opening being attached to the back piece by one or more rows of stitching along the side of the leg, said pocket means at the other side of the opening being disposed within said back piece.

2. In a trouser: pieces forming, respectively, the front and back of the trouser leg, the back piece overlapping the outer face of the front piece; and said front piece having an upper portion defining one edge of a pocket opening, said portion being unattached to the back piece, the front and back pieces being otherwise sewed together at the side of the leg; and means forming a pocket having an opening, said means at one side of the opening being attached to said upper portion, and at the other side of the opening being attached to the back piece by one or more rows of stitching along the side of the leg, said pocket means at the other side of the opening being disposed within said back piece; said pocket forming means, where it is thus attached to the back piece, having a facing of cloth wide enough to cover the space between the two sides of the opening, the rear edge of said facing being disposed within said back piece.

3. In a trouser: pieces forming, respectively, the front and back of the trouser leg, the back piece overlapping the outer face of the front piece; and said front piece having an upper portion defining one edge of a pocket opening, said portion being unattached to the back piece, the front and back pieces being otherwise sewed together at the side of the leg; and means forming a pocket having an opening, said means at one side of the opening being attached to said upper portion, and at the other side of the opening being attached to the back piece by one or more rows of stitching along the side of the leg, said pocket means at the other side of the opening being disposed within said back piece; said pocket forming means, where it is thus attached to the back piece, having a facing of cloth wide enough to cover the space between the two sides of the opening, the rear edge of said facing being disposed within said back piece and the front of said facing having a straight edge where it is sewn to the pocket forming means.

4. In a trouser: front and back pieces of a trouser leg, the forward edge of the back piece overlapping the outer face of the rearward edge of the front piece; a pocket disposed within said front piece and having an opening defined by forward and rearward marginal portions; one or more rows of stitches attaching said rearward marginal portion of said pocket to the inner face of said back piece, said stitches also attaching the overlapping forward and rearward edges of said pieces together; and one or more rows of stitches attaching the forward marginal portion of said pocket to and within said front piece.
